DESIGN FOR A COOKING STOVE

Russell N. Hanson and Sophus Rasmussen, Albert Lea, Minn., assignors to American Gas Machine Company, Albert Lea, Minn., a corporation of Delaware

Application December 7, 1936, Serial No. 66,369

Term of patent 7 years

To all whom it may concern:

Be it known that we, Russell N. Hanson and Sophus Rasmussen, both citizens of the United States and both residing in the city of Albert Lea, county of Freeborn, and State of Minnesota, have invented, jointly, a new, original, and ornamental Design for a Cooking Stove, of which the following is a specification, reference being had to the accompanying drawing, forming a part thereof, wherein,

Fig. 1 is a perspective view of a cooking stove showing our new design;

Fig. 2 is an end elevation in enlarged scale of the same; and

Fig. 3 is a plan view in enlarged scale of the same.

The shading on the drawing represents contrasting color effect.

We claim:—

The ornamental design for a cooking stove, substantially as shown and described.

RUSSELL N. HANSON.
SOPHUS RASMUSSEN.
